METHOD OF REPAIRING LOOPED FABRICS

Application filed June 9, 1930. Serial No. 460,023

This invention relates to improvements in methods of repairing looped fabrics and particularly to an improved method of restoring to original condition knitted fabrics 5 in which runs have been produced by reason of broken threads.

As is well known, when a thread in a looped fabric breaks, the loops supported by the thread unravel or straighten out to form 10 a so-called run. Recently numerous methods have been devised for re-looping the dropped loops and restoring the fabric to its original condition. These methods are practiced, commercially, mainly in connection with 15 hosiery and similar knitted articles of wearing apparel. Methods have also been devised for re-looping the broken thread with the loops supported thereby, but thus far such methods have been devised only to make 20 the repair where but one thread is broken. When two or more threads are broken, the methods heretofore developed can not successfully be used.

It is a primary object of my invention 25 to provide a method for repairing looped fabrics in which loops have been dropped by reason of the breaking of two or more threads of the fabric.

It is another object of my invention to 30 provide a method of repairing looped fabrics in which two or more threads in adjacent courses have been broken by producing a single course of loops connecting the other loops of the fabric in place of the 35 loops previously formed by the broken threads.

By my invention, I am enabled to repair articles which have heretofore been rejected by hosiery menders, generally, and by others 40 engaged in the business of repairing looped fabrics.

The method will be best understood when explained in conjunction with the accompanying drawings in which I have illustrated 45 the essential steps of the method. These drawings are, of course, more or less schematic and are not intended to show with absolute fidelity the construction of the fabric and its appearance at the various 50 stages of my method, but it is believed that

they will adequately impart to those skilled in the art sufficient knowledge of my method to enable them to practice the same.

In these drawings:

Fig. 1 is a diagrammatic view, greatly 55 magnified, of a piece of knitted fabric in which two threads in adjacent courses have been broken, thereby producing runs on both sides of the threads;

Figs. 2 and 3 illustrate the more important 60 steps of my method of repairing as applied to the fabric illustrated in Fig. 1; and

Fig. 4 is a view similar to Fig. 1 showing 65 the fabric completely restored in accordance with my method.

Referring now to the drawings, Fig. 1 illustrates a piece of knitted fabric which has been made in any well known manner and comprising interconnected loops 1. A plurality of the loops have been dropped 70 to form runs 2, 4, and 6, on one side, and 3 and 5 on the opposite side, respectively, of two broken threads 7 and 8. My method contemplates the restoration of the fabric shown in Fig. 1 to its original condition. 75

The first step of my method is to secure together the adjacent ends of the broken threads 7 and 8. This is preferably done by tying the said ends and forming knots 80 10 and 11, at opposite sides of the runs. The tying of the ends of the broken threads 85 is facilitated by first drawing the ends outwardly from the fabric until the ends are long enough to be tied into a knot, whereupon the threads may be pulled back into the fabric, in the usual manner.

Sometimes, when a thread has been pulled out of a stocking the wearer will cut the thread, thus reducing its original length. If that has been done, it will be necessary 90 to secure sufficient lengths of additional or foreign thread to the ends of the broken threads 7 and 8 and tying the additional or foreign thread.

After the ends of the broken threads have 95 been tied together, as shown in Fig. 1, the last step is to secure an additional or foreign thread to one end of the broken threads. In Fig. 1, I have illustrated a foreign thread 12 secured to the right ends 100

of the broken threads 7 and 8, which have been knotted as at 11, since, in performing the re-looping operation, it is necessary to start the work from the right side of the run.

5. It is understood, of course, that in re-looping the dropped loops, the fabric will be stretched over a suitable holder. Any type of repair needle or knitting needle may be employed in the re-looping operation. 10 My method does not depend upon the use of any particular type of holder or needle, but may be carried out by any of these devices now in use.

15. After the additional or foreign thread has been secured to the broken threads in the manner described, the re-looping operation is commenced by re-looping the run 2, as shown in Fig. 2. The foreign thread 12 is then drawn through the last loop 13 of the run 2. Thereupon, the operator reverses the holder upon which the fabric is stretched and re-loops the run 3, the foreign thread 12 being passed through the last loop of this run. 20 The holder is then turned to its original position for the re-looping of the run 4, then reversed for the run 5 and again returned to its original position for the re-looping of the run 6. When each run has 25 been re-looped, the foreign thread 12 is intertwined with the loops until the fabric is in the condition illustrated in Fig. 3. Thereupon the end of the additional or foreign thread 12 is secured to the ends of the threads 7 and 8 which were tied together by the knot 10.

30. In Fig. 4, the fabric is shown as completely restored in accordance with my method. It will be understood that the foreign thread 12 takes the place of the two original threads 7 and 8 in the re-looping operation and that therefore only one course of loops is formed where two courses originally existed. Nevertheless, the repair work 35 done in accordance with my foregoing method is practically invisible, because the loops of the single course formed by the thread 12 will not be twice the length of the ordinary loops, since the tension will be equally distributed to adjacent courses, thus producing some elongation of the loops therein. In other words, while one course replaces two, there is an equal distribution 40 of the elongation of the loops so that the work is practically invisible.

45. By the foregoing method, it is possible for menders to make repairs of knitted fabrics which have heretofore been rejected as being impossible to repair. The possibilities of my method will be readily apparent to those skilled in the art and it will be seen that knitted fabrics, such as hosiery, which have been very seriously damaged 50 may be quite readily restored to original condition. For example, if more than two

threads are broken, any adjacent pair of threads may be secured together while the additional threads may be stretched across the run and tied in the usual manner.

55. What I claim is:

1. The method of repairing looped fabrics damaged by dropped loops resulting from broken threads in adjacent courses which includes the step of securing together the ends of said threads on the same side of 70 said dropped loops.

2. The method of repairing looped fabrics damaged by dropped loops resulting from broken threads in adjacent courses which includes the step of securing together 80 the ends of said threads at each side of the dropped loops.

3. The method of repairing looped fabrics damaged by dropped loops resulting from broken threads in adjacent courses 85 which includes the steps of drawing said threads out of the fabric, securing together the ends of said threads on the same side of 90 said dropped loops, and drawing said threads back into the fabric.

4. The method of repairing looped fabrics damaged by dropped loops resulting from broken threads in adjacent courses which includes securing an additional 95 thread to the ends of said broken threads.

5. The method of repairing looped fabrics damaged by dropped loops resulting from broken threads in adjacent courses which includes securing an additional thread to the ends of said broken threads 100 at one side of the dropped loops.

6. The method of repairing looped fabrics damaged by dropped loops resulting from broken threads in adjacent courses which includes securing an additional 105 thread to the ends of said broken threads, and re-looping the dropped loops with said additional thread.

7. The method of repairing looped fabrics damaged by dropped loops resulting from broken threads in adjacent courses 110 which includes securing an additional thread to the ends of said broken threads at one side of the dropped loops, re-looping the dropped loops with said additional thread, and securing the end of said additional thread to the other ends of said broken threads.

8. The method of repairing looped fabrics damaged by dropped loops resulting from 115 broken threads in adjacent courses which includes securing an additional thread to the ends of said broken threads, re-looping the dropped loops with said additional thread, and forming one course of loops by 120 said additional thread in lieu of the two courses previously formed by said broken threads.

9. The method of repairing looped fabrics damaged by dropped loops resulting 125

from broken threads in adjacent courses which includes securing an additional thread to certain of the broken threads, re-looping the dropped loops with said additional thread, and forming one course of loops by said additional thread in lieu of the two courses previously formed by said broken threads.

10. The method of repairing looped fabrics damaged by dropped loops resulting from broken threads in adjacent courses which includes securing an additional thread to the ends of said broken threads at one side of the dropped loops, re-looping 15 said dropped loops with said additional thread, forming a single course of loops by said additional thread in lieu of the two courses previously formed by said broken threads, and securing the end of said additional thread to the other ends of said broken threads.

In testimony whereof, I affix my signature.

CAROLINE KUDELA.
